MINIMUM ERROR DETECTING CIRCUIT
Franz L. Putzrath, Oaklyn, N.J., assignor to the United States of America as represented by the Secretary of the Air Force
Filed May 19, 1961, Ser. No. 111,410
1 Claim. (Cl. 320—1)

In pattern matching systems such as character recognizers, for example, it is necessary to compare the incoming message with the available store of standard patterns. In many applications this is accomplished in a serial mode so that an error signal is produced the instantaneous voltage of which is proportional to the degree of error between the unknown pattern and the stored pattern. It then becomes necessary to determine when the error signal reaches a minimum value. The purpose of this invention is to provide a circuit for determining when an error signal or, more generally, any complex voltage wave reaches a minimum value.

The manner in which the above purpose is accomplished will be explained in detail with reference to the accompanying drawing in which

FIG. 1 is a schematic diagram of the minimum error detecting circuit, and

FIG. 2 illustrates the operation of the circuit of FIG. 1.

Referring to FIG. 1, error voltage source 1 may be a pattern matching system as mentioned above which produces an error voltage the instantaneous value of which is proportional to the error between patterns to be matched. The circuit of FIG. 1 determines when the error voltage has its minimum value, i.e., when the closest match occurs. A typical error voltage variation as a function of time is shown in FIG. 2. The circuit comprises a condenser C and an output transistor R connected in series and a single pole double throw switching device S for connecting the series elements either across direct current source 2 or through unidirectional device 3 to error voltage source 1. The circuit is initially conditioned by throwing switch S to the right to initially charge condenser C to the voltage V_1 . The switch is then thrown to the left to determine when the minimum error signal occurs. The output voltage giving this information is developed across resistor R.

The operation of the circuit is illustrated in FIG. 2. Consider switch S to be in its right hand position, as illustrated, and condenser C to be charged as a result to the voltage V_1 of source 2. At time $t=0$ switch S is thrown to its left hand or operating position. It will be apparent from FIG. 1 that, in the operating position, source 1, resistor R, charged condenser C and diode 3 are all connected in a series circuit and that current flow in this circuit is limited to the discharge direction by unidirectional device 3. At time $t=0$ the condenser voltage $V_c = V_1$ and the error voltage is greater than V_c . Therefore no current flow occurs in resistor R due to the opposition of diode 3. However, when the error voltage falls below V_c condenser C discharges through diode 3, source 1 and resistor R with V_c falling from V_1 to substantial equality with the error voltage. This discharge produces a negative voltage pulse 4 across R and establishes a new lower value for V_c . No further discharge occurs until the error voltage falls below the newly established value

2

of V_c at which time the condenser discharges further producing another output pulse 5 and establishing another new lower value of V_c . This process continues with an output pulse being produced each time the error signal falls below the last established value of V_c . It is evident that the last pulse in this series, such as pulse 6 in FIG. 2, occurs at the time when the error signal passes through its minimum value.

Although the error signal is usually unipolar, as shown in the example given, this is not a requirement of the circuit. If the error signal should pass through zero and become negative the circuit would still operate satisfactorily provided, of course, that the maximum negative peak is to be taken as the minimum value of the signal. 15 When the error signal becomes negative, condenser C charges through R, with its lower terminal positive, to a voltage equal to the negative peak, this process producing a negative pulse across R as before. Pulses will continue to be produced for any negative peak exceeding 20 the last established negative condenser voltage. The last output pulse to occur therefore establishes when the signal passed through its maximum negative peak.

For proper operation of the circuit, the quality of condenser C should be such that no significant leakage of 25 charge occurs during an operating period of the circuit.

I claim:

A circuit for detecting when the minimum value of a unipolar signal occurs, said circuit comprising: a condenser, a resistor and a unidirectional device; means operative to first charge said condenser to a predetermined voltage greater than the expected minimum value of said signal and then to form a circuit containing, to the exclusion of all other elements connected in or thereto, said signal, said unidirectional device, said charged condenser and said resistor connected in series in a closed loop, with the polarities of said charged condenser and said signal in opposition and with said unidirectional device poled for conduction in the condenser discharging direction; and an output circuit coupled across said resistor whereby an output voltage proportional to the discharge current of said condenser is produced in said output circuit.
